UNITED STATES PATENT OFFICE.

CLINTON H. SMITH, OF EAST ORANGE, NEW JERSEY.

CUFF.

1,080,380.

Specification of Letters Patent.

Patented Dec. 2, 1913.

Application filed August 21, 1909, Serial No. 513,924. Renewed October 25, 1913. Serial No. 797,328.

To all whom it may concern:

Be it known that I, CLINTON H. SMITH, a citizen of the United States, and a resident of East Orange, in the county of Essex 5 and State of New Jersey, have invented certain new and useful Improvements in Cuffs, of which the following is a specification.

My invention relates to the manufacture of cuffs and more particularly to cuffs which 10 are permanently secured to the sleeves of a shirt during its manufacture.

The main object of my invention is to provide a cuff which will not crack at the edge after it has been laundried and bent 15 to insert the cuff-buttons.

A further object is to provide a cuff which will have the above advantage and at the same time retain the reinforced, stiff edge and bead common to cuffs of good make.

20 A still further object is to attain a cuff which will have the above advantage of not cracking and at the same time still retain the usual smooth outward appearance.

As is well known it is now the common 25 practice to manufacture shirts, especially the higher grade ones, with cuffs permanently attached to the sleeves. When the shirts are laundried a few times and the cuffs bent around to insert the buttons or 30 links, the cuffs crack at the outer edge which practically ends the life of the entire shirt even though the shirt proper remains perfectly good. This condition becomes very 35 annoying and expensive especially in the higher priced shirts, and some manufacturers, recognizing this defect, have provided an extra pair of cuffs with each shirt, to be attached thereto when the original cuffs crack. While this has lengthened the life 40 of the shirt, it has been found that even after the second pair of cuffs have cracked the shirt proper is still in first class condition. Further in the latter instance, it is necessary to employ some one to remove the 45 old cuffs and attach the new ones as it requires more or less skill which is ordinarily not possessed by a layman. As is well known, this cracking of the cuff is due to the great thickness of material at the edge 50 of the cuff which custom demands should be very stiff to properly hold its shape, custom also demanding that a bead be provided. By my invention, to give a smooth 55 appearance to the cuff, some of the thicknesses of material in the reinforced edge are cut away at the middle of the cuff where

it bends when turned to insert the cuff links and in such a way that the edge still retains its stiffness and the customary bead.

By constructing cuffs in accordance with 60 my invention it has been found, by actual practice, that they can be laundried and bent a great many times without in the least way showing any signs of cracking and in fact many more times than any shirt 65 could stand being laundried and it is thus assured that cuffs so constructed will be of equal life with the shirt to which they are attached.

While the greatest use for my invention is 70 in cuffs attached to shirts, it will be understood that my invention is not limited to this style of cuffs as it can equally well be applied to other styles without departing from the spirit thereof.

75 To these ends my invention consists in the improved cuff hereinafter more particularly described and then specified in the claims.

In the accompanying drawings Figure 1 80 is a developed plan of a cuff constructed in accordance with the preferred manner of carrying out my invention, the material of the cuff being shown sewn together previous to turning. Fig. 2 is a transverse section on the line X X Fig. 1 and showing the thickness of material greatly exaggerated. Fig. 85 3 is a similar section after the cuff has been turned and the stitching seam run to secure the material in its final position. Fig. 4 is a similar section to Fig. 3 but taken at a 90 point beyond the cut out part of the edge.

In constructing the cuff, two pieces of the body cloth, 1, 2, are placed one upon the other and upon them is placed the shrunk interlining 3 doubled upon itself and consisting preferably of heavier and stiffer material than the body cloth, 1, 2, and by means of which the cuff is given its desired stiffness. The different pieces are then sewed together at their top and sides by the 100 running seam 4 located approximately $\frac{1}{4}$ inch from the edge of the superposed layers. Preferably both thicknesses of the interlining 3 at the middle of the cuff are cut away, starting at the edge and extending to 105 a depth nearly reaching the running seam 4, but preferably leaving a small amount of material beyond the seam. The cut preferably graduates in depth from its starting point at the edge toward the seam, the bottom or lowermost part of the cut preferably 110 running parallel with the seam 4 for a short

distance either side of the middle line of the cuff and thereby when the cuff is turned over there will be no sudden great difference in thickness in the cuff which would 5 mar its outer surface when ironed. Also to further avoid any sharp distinction or shoulder at the beginning of the cut away portion, the side lines of the cut in the different layers do not coincide, the cut away 10 part 5 of the upper layer being longer than the cut 6 of an intermediate layer. After the desired portions are cut away, the cuff is then turned right side out to bring the two pieces of body cloth 1, 2 on the outside 15 of the interlining as shown in Fig. 3. When turned the layer of body cloth 2 which comes on the inside of the cuff is drawn down to form the usual bead 7 and the stitching seam 8 is run along close to the edge of the 20 interturned part beyond the running seam 4. By allowing a little of the material of the interlinings to remain beyond the running seam 4 at the cut-out portions 5 and 6, a continuous bead 7 is obtained along the edge 25 of the cuff and thereby the cuff will present the same outward appearance as cuffs constructed in the ordinary way, but owing to the interlinings having been cut away at the place where the cuff bends, the edge is 30 not so unyielding and liable to crack and owing to the graduated thickness from the heaviest toward the thinnest part, any mar- ring or distinct shoulders will not appear.

when the cuff is ironed. It will be obvious 35 that the cut-out portions might take other shapes without departing from the spirit of my invention, but for the reasons stated above and by actual practice, it is found that when formed as shown and described the best results are attained.

40 What I claim as my invention is:

1. A cuff provided with a reinforced edge and having one or more thicknesses of the inner material cut out between the running seam and the stitching seam, the interlinings at said cut out portion being fastened 45 down by said running seam.

2. A cuff provided with a reinforced edge between the running seam and the stitching seam, said reinforcement consisting of 50 superposed layers of inter-lining and having portions of said inter-lining between said seams cut away, whereby the thickness of the edge between said seams is less at the 55 middle of the cuff than at other points and the inter-linings gradually increasing in thickness as the distance increases from the middle of the cuff as and for the purpose described.

Signed at New York in the county of 60 New York and State of New York this 20th day of August A. D. 1909

CLINTON H. SMITH.
